TIMING DEVICE

Paul A. Coffman, Jr., Kansas City, Mo., assignor
to Omega Machine Company, Kansas City, Mo.,
a corporation of Missouri

Application July 31, 1942, Serial No. 453,089

7 Claims. (Cl. 200—33)

My invention relates to timing devices, and more particularly to devices for controlling the time interval that a circuit, or circuits, are energized relative to the time interval that such circuit, or circuits, are de-energized.

It is a purpose of my invention to provide a timing device of the above mentioned character that is simple and cheap in construction and at the same time is accurate in operation and is capable of accurate adjustment between such limits that the circuit controlled by the timing device can be either open or closed from 100% to 0% of the total time in any time interval.

My invention is particularly adapted for use in connection with the control of industrial operations, to determine the percentage of the total time during any given time period that a device will be in operation. In this manner the timing device can be used to accurately control the rate of operation of such devices as feeding devices, and can also be used to control temperatures and various other varying factors in which the operation of a heating element, a motor, or other electrically controlled or actuated means is operated in proportion to the length of time out of any repeating time interval that a circuit is closed, or energized. My timing device is also adapted for use in conjunction with time delay switches, or similar devices, to begin an operation at certain time intervals, which operation may continue for a period, determined either by the other switching device, or by the timing device. Such a timing device as that constituting my invention is of such wide application that it can be used generally for any purpose where the time interval during which a circuit is to be in operation or not in operation, is of importance. The time interval during which a cycle of operations takes place can be made very short or very long, as may be found desirable. The device can be so operated that the cycle of operations can be repeated a plurality of times per second, a plurality of times per minute, or per hour, or as infrequently as once per day, should this be found desirable. However, the device is particularly adapted for use where the time interval for each cycle is relatively short, as the device is particularly adaptable for such use, due to the fact that it is capable of such accurate operation as to permit of such use without any appreciable error in the results produced thereby.

It is a particular purpose of my invention to provide in combination with an operating circuit and an electrical supply line, means for controlling the time intervals over which the cir-

cuit is connected with and disconnected from the supply line, comprising a plurality of switches and means for actuating these switches, comprising a member rotating at a constant speed, and means for adjusting the position of one switch relative to another thereof, whereby the time intervals are controlled.

More particularly my invention comprises a cam driven at a constant rate of speed, which is provided with high and low portions and switch operating members engaged with the surface of the cam for controlling the switches, whereby the circuits are controlled to determine the time intervals referred to, one of said switches being mounted in fixed position so that the switch operating member associated therewith will be in a predetermined station in the travel of the cam around its axis of rotation, and another of said switches being mounted for adjustment in an arc about the axis of rotation of said cam so that the switch operating member associated therewith will be adjustable to vary the station thereof relative to the cam and relative to the previously referred to switch.

25 My invention specifically comprises means for controlling the circuit so as to control the time intervals during which the same is connected with a source of electrical energy and disconnected from said source of electrical energy, comprising a cam and a switch mounted for adjustment about the axis of rotation of the cam, so that the operating member for controlling the position of said switch acted on by the cam will assume different positions about the axis of rotation of the cam, and means for adjusting the position of said adjustable switch, including means for indicating the position to which the switch has been adjusted. Said means specifically comprises an arm mounted for rotation about the axis of rotation of the cam having the switch and its operating means mounted thereon, and means for swinging said arm about said axis as a center through an arc which is, preferably, 180°, and operating means therefor including a dial indicating the position of the arm on an appropriate scale, which is, preferably, calibrated in hundredths to indicate percentages.

In the preferred embodiment of my invention 50 a pair of switches is provided, which switches are included in a controlled circuit in such a manner that when said switches are in a corresponding position relative to each other, the controlled circuit is disconnected from the supply circuit, and 55 when said switches are in an opposed position

relative to each other, the controlled circuit is connected with the supply circuit, and the switches are provided with actuating means including the aforementioned cam and switching means that are so arranged that the same can be adjusted, so that the operating members thereof are in axial alignment with each other transversely of the cam and thus in engagement with the same part of the cam to be actuated thereby, so as to always have corresponding positions, whereby the controlled circuit will be continuously disconnected from the supply circuit, or can be positioned so as to be diametrically opposite each other, which would result in the switches always having opposed positions, resulting in the controlled circuit being continuously connected with the supply circuit, or the adjustable switching means can be moved to any position between the two positions, so as to control the period of time during which the switch operating members of the two switches are on the same portion or a different portion of the cam, to determine the length of time during any single rotation of the cam that the switches are in a corresponding or opposed position.

Other objects and advantages of my invention will appear as the description of the drawings proceeds. I desire to have it understood, however, that I do not intend to limit myself to the particular details shown or described, except as defined in the claims.

In the drawings:

Fig. 1 is a top plan view of my improved timing device.

Fig. 2 is a front elevational view thereof.

Fig. 3 is a diagram of the circuit employed in my improved timing device.

Fig. 4 is a vertical sectional view through the switch adjusting means and cam, with the switches, wiring and driving mechanism for the cam omitted, certain parts being in elevation.

Fig. 5 is a fragmentary view showing the cam and the switches cooperating therewith in elevation, and the driving pin for the cam in section, the view being taken substantially on the line 5-5 of Fig. 1, and showing the switches in the position shown in Fig. 1.

Fig. 6 is a diagrammatic view, similar to Fig. 5, showing the switches in a relative position such that the controlled circuit will be constantly open, or de-energized, and

Fig. 7 is a similar view to Fig. 6, showing the switches in a position in which the controlled circuit will be constantly closed, or energized.

Referring in detail to the drawings, my invention is shown as being mounted on any suitable frame 10 having a transverse member 11 and a front plate 12. Mounted on the transverse member 11 in any suitable manner, as by means of the bolt-like members 13 and spacing sleeves 14, is a motor operating at constant speed, preferably, an alternating current synchronous induction motor 15. A reduction gearing 16 may be provided for driving the shaft 17 at a desired number of revolutions per minute, said shaft 17 having a collar 18 fixed thereto, which is provided with a driving pin 19.

A rotatable shaft-like member 20 is mounted on the wall 12 for rotation in a bearing provided thereon and extends through an opening in the wall 12, the same being manually rotatable in a manner to be described below. A long socket or bearing opening 22 is provided in the member 20, which receives the integral shaft portion 23 on the cam 24, which has an opening 25 therein, into which the driving pin 19 extends. Thus the

cam 24 is rotated about the axis of the shaft 17 and, also, of course, about the axis of the shaft 23 and the axis of the rotatable shaft-like member 20. The cam 24 is provided with a high portion 26 and a low portion 27, there being slightly inclined shoulders 28 and 29 at the junction of the cam portions 26 and 27, said cam rotating in the direction of the arrows in Figs 5, 6 and 7.

Cooperating with said cam 24 is shown a pair of switches 30 and 31. Said switches are of a type that move from one alternative position to the outer alternative position thereof with a snap action by a minimum amount of movement of an operating member for the switch, such as the type of switch shown in the patent to Phillip K. McGall 1,960,020, patented May 22, 1934, the operating members for the switches comprising the arms 32 and 33 extending therefrom, said operating members 32 and 33 moving the movable elements of the switches indicated in the circuit diagram shown in Fig. 3 by the numerals 34 and 35, from contact with one stationary contact 36 to contact with another stationary contact 37, in the case of the movable contact element 34, and from a position in engagement with one stationary contact element 38 to a position in engagement with another stationary contact element 39, in the case of the movable contact element 35, the switches 30 and 31 being thus identical in construction and in operation so that a movement of the operating member 32 from one predetermined position to another predetermined position will have the same effect in moving the movable contact element 34 of the switch 30 from one alternative position to another, as will such a movement of the operating member 33 on the movable contact element 35 of the switch 31. The operating member 32 is provided with a projection 40 thereon engaging the surface of the cam 24 and the operating member 33 is provided with a similar projection 41 thereon, engaging the surface of said cam element 24, the projections 40 and 41 being of a character that the same will present a narrow edge to the surface of the cam, as will be obvious from Fig. 5.

The shaft-like member 20 is provided with an enlarged hub portion 42 at one end thereof, which is integral therewith, and a bearing member 43 is fixed, as by solder 21, to the rear face of the front plate 12 of the frame 10 having a long bearing opening therein, so as to provide for accurate co-axial rotation of the member 20 about the axis of the shaft 17 and accurate co-axial rotation of the cam 24 about the axis of said shaft 17. Said hub portion is provided with an arm 44, preferably, integral therewith, projecting radially therefrom, which arm is of a flat plate-like character and of any desired shape to provide a secure mounting for the switch member 30, which is mounted in fixed position on said arm 44 by means of the securing elements 45.

It will be obvious that as the arm 44 is rotated about the axis of the shaft-like member 20, and thus about the axis of rotation of the cam 24, the edge of the projection 40 in engagement with the cam will move to various positions relative to the projection 41 about the axis of rotation of the cam 24, so that either the high portion 26 or the low portion 27 of the cam will be engaged by said projections 40 and 41 at the same time or at different times, or will both be in engagement with the same portions of the cam for different time intervals. The cam is

so made that the high portion 26 thereof and the low portion 27 thereof are of substantially equal length, each occupying 180° of the cam surface, except for the slightly inclined connecting portions 28 and 29. The inclination of the portions 28 and 29 is only such that the projections will ride up the same without catching on the offsets in the cam thus provided, and will not drop violently onto the surface of the cam from the high portion to the low portion thereof, as the steeper the inclination the more quickly, of course, the change in position of the switch operating members 32 and 33 will take place.

Any suitable means for adjusting the position of the movable switch member 30 may be provided, comprising means for rotating the shaft-like member 20 about its axis. A simple form of such adjusting means comprises a disk-like dial member 46, which may be provided with graduations 47 thereon, for indicating the position that the member 46 assumes, the graduations shown being such as to divide an arc of 180° on the disk 46 into one hundred parts, so as to each indicate one percent of the total rotation of the arc of 180°, only some of the graduations being shown in the drawings for the sake of clearness. The disk-like member 46 is fixed to the shaft-like member 20 by means of a set screw 48 or any similar means. An arrow or similar mark 50 serving as an indicator cooperating with the markings on the disk-like member may be provided on the front plate 12. The means for rotating the disk-like member 46, preferably, comprises a knob 54 integral with the disk-like member 46.

While the cam is described as having high and low portions covering an arc of substantially 180° and the scale is described as being graduated over an arc of 180°, obviously by the use of a plurality of pairs of switches and shorter arcs, similar results can be obtained. Of course, the longer the arc through which the adjustment of the movable switch is made, the finer the adjustment can be made on the scale provided, by the ordinary operator of the device.

A cord 59 may be connected with any suitable electric outlet for connecting the timing device with a supply circuit, which would, of course, have to be an alternating current supply, if an alternating current motor of the character described is utilized. Said cord is provided with conductors 60 and 61, which constitute the line wires, and any suitable switch 62 having an operating member 63 may be provided in one of the line wires for throwing my timing device into and out of operation, the switch establishing connection between the terminal 64 and the terminal 65, thus connecting the one line conductor 61 with the conductor 66 leading to one terminal of the motor 15, the other terminal of the motor being connected directly with the line wire 60. The switch 62 is not included in the circuit diagram in Fig. 3, as it is not of importance to the operation of the device. A cord 67 extends from the device to the controlled circuit, containing the conductors 68 and 69 leading to said controlled circuit, the conductor 68 being connected directly with the conductor 60, being shown as being connected to the same terminal of the motor 15 to which the conductor 60 is connected. A conductor 70 extends from the terminal 65, and thus from the line wire 61 to the movable contact element 34 of the switch 30,

and the conductor 69 extends from the movable contact element 35 of the switch 31.

The switch 31 is mounted in fixed position on the front plate 12 of the frame 10 by any suitable means, as by means of a bracket 71 secured to said plate 12 by means of securing elements 72, the switch 31 being secured to the bracket by means of the securing elements 73 in a well known manner. A conductor 74 extends from the stationary contact 37 of the switch 30 to the stationary contact 38 of the switch 31, and a conductor 75 extends from the stationary contact 36 of the switch 30 to the stationary contact 39 of the switch 31. Assuming that the movable contact elements 34 and 35 will be in the position shown in Fig. 3 when the projections 40 and 41 on the operating members 32 and 33 are on the high portion 26 of the cam, it will be obvious that the controlled circuit, indicated generally by the numeral 76, will be disconnected from the line wires 60 and 61. However, should the operating member 32 drop off the high portion of the cam 26 onto the low portion 27 thereof while the operating member 33 is still on the high portion of the cam, the movable contact member 34 will then be instantaneously moved from engagement with the stationary contact 36 to engagement with the stationary contact 37 and the circuit from the line to the controlled circuit 76 will be completed, the movement being substantially instantaneous due to the snap action characteristics of the movable switching elements 34 and 35. The same result would occur if the operating member 33 descended to the low portion 27 of the cam 24 while the operating member 32 were still in engagement with the high portion 26 of the cam, as then the contact member 34 would remain in the position shown in Fig. 3, but the contact member 35 would move into engagement with the stationary contact member 39 to complete the circuit through the pair of switches. A similar movement in the opposite direction would take place whenever an operating member moved due to traveling from the low portion 27 of the cam to the high portion 26 thereof.

It will accordingly be obvious that if the projections 40 and 41 of the operating members are in engagement with the same portion of the cam 24 the controlled circuit will be disconnected from the line wires, and that when said projections 40 and 41 are in engagement with different portions of the cam, that is, one with the high portion and the other with the low portion thereof, the circuit will be completed between the line wires 60 and 61 and the controlled circuit 76. It will also be obvious that the length of time that the circuit will be either completed or not completed between the line wires and the controlled circuit will depend upon the relative position of the projections 40 and 41 on the operating members 32 and 33. Thus when these are in the position shown in Fig. 6, in which the projections 40 and 41 are aligned with each other transversely of the cam, exactly the same portions of the cam will be engaged at all times by said projections as said cam rotates, and the change in position of the operating members 32 and 33, due to their travel from the high to the low portion of the cam, and vice versa, will take place simultaneously, and thus the circuit between the conductors 69 and 70 will be constantly open and the controlled circuit will be constantly disconnected from the line wires and will thus be continuously out of operation.

However, when the adjustable switch member 30 is moved to the position shown in Fig. 7 the projection 40 thereon will always be diametrically opposite the projection 41 on the operating member 33, and thus said projection 40 will always engage the low portion 27 of the cam during the interval that the projection 41 engages the high portion 26 of the cam, and vice versa, the change from the one portion of the cam to the other at a distance of 180° from each other taking place simultaneously for the two operating members 32 and 33, and these will thus be always in relatively opposite positions, maintaining the movable contact elements 34 and 35 always in opposite positions, and thus keeping the conductors 69 and 70 constantly connected with each other and the controlled circuit 76 constantly connected with the line wires and thus constantly in operation.

It will be obvious that any position of the switch member 30 between the two extreme positions shown in Figs. 6 and 7 will cause the circuit between the conductor 69 and the conductor 70 to be open and closed different intervals of time and the length of time that the circuit will be closed will decrease constantly as the projection 40 on the operating member 32 approaches the projection 41 on the operating member 33 as said switch member 30 is rotated by rotation of the arm 34 by means of the knob 54, and that the proportion of any entire time interval that the circuit is closed, down to the time required for one revolution of the cam 24 will be in direct proportion to the arcuate movement of the arm 44 from the position in which the operating member is shown in Fig. 6 to that shown in Fig. 7.

What I claim is:

1. The combination with a pair of switches each having a movable contact member, a switch operating member on each switch, and means for constantly determining the simultaneous position of said movable contact members, comprising a shaft, cam means fixed on said shaft, said cam means having high and low portions, means for rotating said shaft at a substantially constant speed, means on said operating members continuously engaging said cam means, and rotatable means for adjusting the position of one of said switches, about the axis of rotation of said shaft relative to the other thereof, to hold the operating member thereof in a position corresponding to that of the operating member of the other switch through from zero to one hundred percent of each revolution of said shaft, said rotary means for adjusting the position of one of said switches being connected to a dial with means thereon indicating its position and means for moving said dial.

2. In a device of the character described, a plurality of switches each comprising a pair of stationary contact members and a movable contact member movable back and forth between two alternative positions with said movable contact member in engagement with one of said stationary contact members in one of said positions and with the other of said stationary contact members in the other of said positions, a shaft, cam means fixed thereto having high and low portions each of uniform height, throughout the length thereof and each of substantially equal length, means for continuously rotating said shaft at a determined speed, a switch operating member on each switch the position of which determines the position of the movable contact member of said switch, said operating members

each continuously engaging said cam means to each occupy two alternative positions, for intervals of equal length while alternately engaging said high and low cam portions to move the movable contact member it operates from engagement with one of said stationary contacts and into engagement with the other thereof upon engagement with one of said cam portions and out of engagement with said other stationary contact and into engagement with said one stationary contact upon engagement with the other of said cam portions, and means for adjusting the position of said switches relatively through an arc substantially equal to that through which each of said cam portions extends to hold the operating members thereof in a corresponding position through from zero to one hundred percent of each revolution of said shaft.

3. The combination with a pair of switches each comprising a pair of stationary contact members and a movable contact member movable alternately into engagement with said stationary contact members, a switch operating member on each switch the position of which determines the position of the movable contact member of said switch, and means for constantly determining the simultaneous position of said movable contact members, comprising cam means having high and low portions of uniform height throughout their length, each of said cam portions having a length of substantially 180°, means for rotating said cam means at a substantially constant speed comprising a shaft fixed thereto, means on said operating members continuously engaging said cam means, and rotatable means for adjusting the position of one of said switches about the axis of rotation of said cam means relative to the other thereof through an arc of substantially 180°, to hold the operating member thereof in a position corresponding to that of the operating member of said other switch through from zero to one hundred percent of each revolution of said shaft.

4. In a device of the character described, a plurality of switches each comprising a pair of stationary contact members and a movable contact member movable back and forth between two alternative positions with said movable contact member in engagement with one of said stationary contact members in one of said positions and with the other of said stationary contact members in the other of said positions, a shaft, cam means fixed thereto having high and low portions each of uniform height, throughout the length thereof and each of substantially equal length, means for continuously rotating said shaft at a determined speed, a switch operating member on each switch the position of which determines the position of the movable contact member of said switch, said operating members each continuously engaging said cam means to each occupy two alternative positions, for intervals of equal length while alternately engaging said high and low cam portions to move the movable contact member it operates from engagement with one of said stationary contacts and into engagement with the other thereof upon engagement with one of said cam portions and out of engagement with said other stationary contact and into engagement with said one stationary contact upon engagement with the other of said cam portions, and means for adjusting the position of said switches relatively through an arc substantially equal to that through which each of said cam portions extends to hold the operating members thereof in

a corresponding position through from zero to one hundred percent of each revolution of said shaft, said adjusting means having means for indicating the adjustment thereof.

5. The combination with a pair of switches each comprising a pair of stationary contact members and a movable contact member movable alternately into engagement with said stationary contact members, a switch operating member on each switch the position of which determines the position of the movable contact member of said switch, and means for constantly determining the simultaneous position of said movable contact members, comprising cam means having high and low portions of uniform height throughout their length, each of said cam portions having a length of substantially 180°, means for rotating said cam means at a substantially constant speed comprising a shaft fixed thereto, means on said operating members continuously engaging said cam means, and rotatable means for adjusting the position of one of said switches about the axis of rotation of said cam means relative to the other thereof through an arc of substantially 180°, to hold the operating member thereof in a position corresponding to that of the operating member of said other switch through from zero to one hundred percent of each revolution of said shaft, said adjusting means having means for indicating the adjustment thereof.

6. In a device of the character described, a pair of switches each having a pair of stationary contacts and a movable contact member movable back and forth between two alternative positions with said movable contact member in engagement with one of said stationary contacts in one of said positions and with the other of said contacts in the other of said positions, a shaft, cam means coaxially fixed on said shaft having high and low portions each of substantially uniform height and each of equal length, means for rotating said shaft at a substantially constant speed, a movable switch operating member on each switch the position of which determines the position of the movable contact member of said switch, said operating members engaging said cam means, one of said switches being mounted in fixed position with its operating member occupying a fixed station in the path of movement

of said cam means, a member mounted for rotation about the axis of said shaft, an arm of fixed length extending therefrom, the other of said switches being mounted on said arm for movement therewith in an arcuate path about the axis of rotation of said shaft to adjust the station of its operating member in the path of movement of said cam means through an arc substantially equal to that through which each of said cam portions extends, means for rotating said member carrying said arm through an arc substantially the length of each of said cam portions, and means rotatable with said last mentioned member for indicating the adjustment of the position of said station.

7. In a device of the character described, a pair of identical switches each comprising a pair of stationary contacts and a movable contact member movable back and forth between two alternative positions, with said movable contact member in engagement with one of said stationary contacts in one position thereof and with the other stationary contact in the other position thereof, the stationary contacts of one switch being electrically connected each with one of the stationary contacts of the other switch to connect said movable contact members of said pair of switches in series in one relative position thereof and disconnect said movable contact members from each other in the other relative position thereof, a shaft, cam means fixed coaxially on said shaft, having high and low portions each of substantially uniform height, and each extending around substantially 180° of the face of said cam means, means for continuously rotating said shaft at a determined speed, a movable switch operating member on each switch the position of which determines the position of the movable contact member of that switch, said operating members continuously engaging said cam means, and means for adjusting the position of one of said switches relative to the other thereof about the axis of rotation of said cam through an arc of substantially 180° to adjust the position of the operating member thereof about the axis of said cam means to any position between one in which said movable contact members are continuously connected in series to one in which the same are continuously disconnected.
